(57) **CLAIM**

The ornamental design for a linear surgical stapler, as shown and described.

DESCRIPTION

FIG. 1 is a perspective view of a linear surgical stapler, showing our new design;

FIG. 2 is a front elevational view of the linear surgical stapler of FIG. 1;

FIG. 3 is a rear elevational view of the linear surgical stapler of FIG. 1;

FIG. 4 is a left elevational view of the linear surgical stapler of FIG. 1;

FIG. 5 is a right elevational view of the linear surgical stapler of FIG. 1;

FIG. 6 is a top plan view of the linear surgical stapler of FIG. 1;

FIG. 7 is a bottom plan view of the linear surgical stapler of FIG. 1;

FIG. 8 is a perspective view of another embodiment of a linear surgical stapler, showing our new design;

FIG. 9 is a front elevational view of the linear surgical stapler of FIG. 8;

FIG. 10 is a rear elevational view of the linear surgical stapler of FIG. 8;

FIG. 11 is a left elevational view of the linear surgical stapler of FIG. 8;

FIG. 12 is a right elevational view of the linear surgical stapler of FIG. 8;

FIG. 13 is a top plan view of the linear surgical stapler of FIG. 8; and,

FIG. 14 is a bottom plan view of the linear surgical stapler of FIG. 8.

The stapler features shown in broken lines are unclaimed environment, and form no part of the claimed design.

1 Claim, 8 Drawing Sheets
